Inventor:

John Quincy Reed

UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S POLONAISE.

SPECIFICATION forming part of Design No. 14,920, dated March 25, 1884.

Application filed February 13, 1884. Term of patent 3½ years.

To all whom it may concern:

Be it known that I, JOHN QUINCY REED, of the city, county, and State of New York, have invented and produced a new and original Design for a Pattern of a Lady's Polonaise, (numbered 9,132;) and I do hereby declare that the engraved prints accompanying this specification convey to any one accustomed to using paper patterns a clear understanding of how a garment made up by the pattern will appear. The design shows closely-fitted fronts, that fall at the center in a short point, over a deep, narrow tablier drapery, exhibiting gatherings in its back edges, and descends at the sides in deep, wide draperies, also displaying gatherings at their back edges and overlapping the tablier at their front edges; a closely-fitted back,

that exhibits underfolded plaits at the lower ends of its middle body-seams, and displays draping-plaits in its front edges, and draping-plaits and shirrings at the center, falling shorter at the left side than at the right, where it is deep and square; coat-sleeves, and a standing collar.

What I claim as my invention, and desire to secure by Letters Patent, is—

The design for a lady's polonaise, as shown in the engraved prints accompanying this specification.

JOHN QUINCY REED.
